UNITED STATES PATENT OFFICE.

GEORGE A. MOSS, OF SAN FRANCISCO, CALIFORNIA, ASSIGNOR TO MARY L. MOSS, OF SAN FRANCISCO, CALIFORNIA.

GAGE FOR SCRIBING WORK.

1,041,145.

Specification of Letters Patent.

Patented Oct. 15, 1912.

Application filed February 6, 1912. Serial No. 675,864.

To all whom it may concern:

Be it known that I, GEORGE A. Moss, a citizen of the United States, residing in the city and county of San Francisco and State 5 of California, have invented certain new and useful Improvements in Gages for Scribing Work, of which the following is a specification.

The hereinafter described invention relates to an improved tool for the use of carpenters in obtaining an accurate outline measurement of the work to which a piece of wood work is to be united, as, for instance, in connection with the fitting of a partition 15 to the existing ornamental mill-work within a building, whereby the piece to be fitted may be cut to make a perfect fit or joint with the surface of the existing wood-work to which it is to be joined; the object of the 20 invention being the production of a simple, inexpensive, accurate and positive gage for use in obtaining an accurate reproduction or outline of the piece or molding to which the new work is to be joined or fitted, by 25 means of which the taking of repeated measurements thereof and the cutting of the board or piece to be fitted may be avoided.

To comprehend the invention reference should be had to the accompanying drawings, wherein—

Figure 1 is a plan view of the improved gage with its cover plate and the presser plate partly broken away. Fig. 2 is a longitudinal sectional view taken on line 35 $x'-x'$ Fig. 1 of the drawings. Fig. 3 is a detail view illustrating the improved gage as applied for securing a measurement of a piece of molding. Fig. 4 is an enlarged detail view of one of the gage pins removed 40 from the holder. Fig. 5 is a broken view illustrating the cover plate detached from the holder.

In the drawings, the numeral 1 is used to designate what shall be termed a holder for 45 the gage pins, the same comprising a flat plate provided with the upturned ends 2, between which the presser plate 3 is situated. The presser plate 3 is held in place against displacement by means of the end lugs 4 50 projecting therefrom fitting within the vertical slots 5 formed in the flanged ends 2 of the holder 1.

Within the holder 1 and between the inner 55 face thereof and the under face of the presser plate 3 is located a series of horizontally

disposed independently slidable alined gage-fingers or bars 6, which normally project a pre-determined distance beyond the inner horizontal edge a thereof. These gage-fingers, pins or bars are of a uniform 60 length, and one end of each is reduced to a point, while the opposite end is preferably formed with a downwardly extended flange, projection or scribing point 7.

The presser plate 3 is held down onto the 65 upper surface of the row of slidable gage-fingers, pins or bars 6 by means of the cover plate 8, which plate rests on the flanged ends 2 of the holder 1, being cut away at each end to provide seats 9 for the reception of the 70 shoulders or ears 10 upwardly projected from the flanged ends 2 of the holder 1.

Through each end of the cover plate 8 and the shoulders or ears 10 of the holder is extended a transverse bore 11 for the reception of a securing or lock pin 12, by means of which the said cover plate is locked to the ends of the holder 1.

To obtain a frictional hold between the slidable adjustable gage-pins, bars or fingers 80 6 and the presser plate 3, a layer 13 of felt or textile material is secured to the under face of the presser plate 3, and the said plate is held firmly pressed against the gage-pins, bars or fingers 6 to hold the same in locked 85 position, by means of the tension thumb-screws 14 which work through the cover plate 8 and bear against the upper surface of the presser plate 3.

When assembled for use the scribing end 90 of the horizontal row of gage-pins, bars or fingers 6 are flush with the outer horizontal edge (designated by the letter a') of the holder 1, the pointed end of each of said gage-pins, bars or fingers being projected 95 from the holder 1 a uniform distance beyond the inner horizontal edge a of the said holder 1.

In using the improved gage for obtaining an accurate outline of the irregular surface of a piece of molding 15 for use in scribing 100 a piece to be fitted thereto, the thumb-screws 14 are first loosened to partly relieve the pressure of the presser plate 3 onto the gage-pins, bars or fingers 6, and the gage then pressed firmly against the outer surface of 105 the molding 15 until the inner horizontal edge a of the holder 1 bears against the same. With the pressure thus applied, the gage-pins, bars or fingers are gradually forced within the holder, the scribing ends 110

- of the said pins being forced a distance beyond the outer horizontal edge a' of the holder to a distance equal to the elevations and depressions of the molding to be fitted.
- 5 The thumb-screws 14 are then screwed down to force the presser plate firmly against the alined series of gage-pins or fingers 6 with sufficient pressure to hold the same securely locked against movement. With the parts
- 10 thus locked, the gage is placed on the piece to be fitted and the scribing points 7 of the adjusted gage pins 6 depressed or forced into the surface thereof to leave thereon an outline of the molding, by means of which
- 15 the scribed piece may be readily cut or sawed for an accurate fit or joint with the molding.

As an aid for readily determining the width of the gage molding, the cover plate 20 is provided adjacent each of its horizontal edges with a scale of measure 16, the same being in inches to one-half of a foot measurement.

The described gage is simple of construction, accurate as to measurement, and readily adapted for moldings or mill work of complex outline.

While by preference each of the gage pins is provided with a scribing point for the 25 formation of an outline marking on the surface of the piece to be fitted to the molding, it is apparent that a pencil may be employed for scribing said piece by following the outline formed by the ends of the gage 30 pins projected beyond the outer horizontal edge a' of the holder 1.

Having thus described the invention what is claimed as new and desired to protect by Letters Patent is—

40 1. In a gage for the work of scribing, the combination with a holder provided with upturned vertically slotted ends, of a series

of horizontally disposed alined gage pins independently slidable therein, a presser plate situated within the holder to bear onto 45 the gage pins and provided with projecting lugs to engage the vertical slots in the upturned ends of the holder, ears upwardly projected from said ends, a cover plate provided with cut outs or seats to receive the 50 said ears, lock pins fitted within a transverse bore in the ends of the cover plate and the ears of the upturned ends of the holder to secure the cover plate thereto, and thumb-screws working through the cover 55 plate for forcing the presser plate against the gage pins.

2. In a gage for the work of scribing, the combination with a holder provided with upturned vertically slotted ends, of a series 60 of horizontally disposed alined gage pins independently slidable therein, and each provided at one end with a scribing point, a presser plate situated within the holder to bear onto the gage pins and provided with projecting lugs to engage the vertical slots in the upturned ends of the holder, ears upwardly projected from said ends, a cover plate provided with cut outs or seats 65 to receive the said ears, lock pins fitted within a transverse bore in the ends of the cover plate and the ears of the upturned ends of the holder to secure the cover plate thereto, and thumb-screws working through the cover plate for forcing the presser plate 70 against the gage pins.

In testimony whereof I have signed my name to this specification in the presence of two subscribing witnesses.

GEORGE A. MOSS.
